UNITED STATES PATENT OFFICE

2,605,769

APPLIANCE FOR THE UPRIGHT FILING OF INDEX CARDS

Béla Lampel, Collonges-sous-Saleve, France

Application August 4, 1947, Serial No. 766,047
In Switzerland October 8, 1942

Section 1, Public Law 690, August 8, 1946
Patent expires October 8, 1962

2 Claims. (Cl. 129—16.7)

1

The present invention relates to an appliance for the upright filing of index-cards, characterized in that it comprises an index-card holder formed by a strip folded lengthwise in such a way as to form a sort of channel intended to fit in a detachable manner on to the upper edge of an index-card, this holder being provided at either end with a means for its suspension on two guide-rods, so that the index-card can be suspended between the two guide-rods and be moved in a direction parallel to it by sliding the holder along these guide-rods.

The annexed drawing shows, as an example, one embodiment of the appliance which is the subject of the invention.

Figure 1 is in perspective.
Figure 2 is a cross-section on a larger scale.

The appliance shown comprises an index-card holder 1 formed by a strip of transparent substance, which may be tinted if desired, folded lengthwise in such a way as to form a sort of channel in which the upper edge of an index-card 3 is intended to be held.

The arm or part 4 of the holder which bears on the obverse side of the index-card 3 is closely parallel with the arm or part 5 of this holder which bears on the reverse side of this index-card. The part 4, however, is longer than the part 5, as can be seen in the drawing.

The distance separating the parts 4 and 5 is such that the index-card 3 is gripped between them when it is inserted into the channel 2, as shown in the drawing. If the holder is looked at from the end, or in cross-section as is the case in Figure 2, it will be seen that it is slightly bent at 6, so that its lip or upper part 7 forms an angle, of about 30° for example, with its lower part. The back part 5 of the holder extends approximately as far as this bend.

The holder 1 is slightly longer than the index-card 3. It is provided near either end with a notch 8 extending from its lower part to about halfway up its height. These notches 8 are intended to ride on two parallel guide-rods fitted in a drawer or cabinet not shown. These guide-rods may be horizontal or slightly inclined, the rear end being slightly higher than the fore end, giving a slope of, for example, 6% in order to increase the visibility of the index-cards. The holder 1 may have two notches near either end, which would allow of moving certain cards sideways when they are needed to be more conspicuous than the others, the number of guide-rods still being two.

The index-card 3 bears, at the place coincid-

ing with the bend 6 when it is fitted in the holder 1, a row of slits 9 which are intended to facilitate the folding of the index-card in the interior of the channel 2 at the bend of the holder 1.

5 The front part 4 of the holder bears three small tongues 10 punched out in it and projecting upwards inside the channel 2. These tongues 10 constitute a means of fixing the index-card 3 in the holder 1. As can be seen in Figure 2, each 10 of these tongues 10 penetrates one of the slits 9 and thus prevents the index-card from accidentally slipping out of the holder. All that is needed to pass the tongues 10 through the slits 9 is to open out slightly the parts 4 and 5, which 15 is easy, as the substance of which the holder is made is slightly elastic. This substance is, for example, Celluloid or a transparent plastic matter such as rhodoid, rhodialine, etc.

It will be noted that the slope backwards of 20 the upper part of the holder 1 and of the index-card allows of the easy reading of the indications appearing on this part of the card. The reading is, moreover, facilitated by the fact that a group of cards can be easily moved away from 25 the others by sliding them along the guide-rods.

The holder 1 is provided with a series of slots 11 in the fold of the channel which are intended for the passage of the heads of flagging devices 12 in the form of small plates, of which the body 30 13, less thick than the width of the slots 11, fits into the channel between the index-card and the part 5 of the holder. In the example shown, these flagging devices are T-shaped, the horizontal branch forming the body and the vertical branch the part serving as flag and projecting 35 through one of the slots 11. So as to obviate any accidental movement of the flagging devices 12 in relation to the holder 1, these devices bear a rib 14 near the base of the flag projecting above the 40 holder. This rib lies outside the channel when the device is in place, as can be seen in the drawing. The passage of this rib through the slot 11 requires sufficient effort to obviate any accidental detachment of the flag.

45 What I claim is:

1. An indexing device, for use in combination with and to be mounted for slidable movement upon a pair of spaced parallel guide rods, comprising a card member having a body portion terminating at its upper end in a lip bent at an angle of approximately thirty degrees (30°) with respect to the said body portion and having formed therein along said bend line a plurality of spaced horizontal tongue receiving slits; a folded strip 50 of transparent material, one arm of which is

longer than the other, having a plurality of flagging device receiving slots formed in the fold line thereof encompassing said lip with the shorter of said arms being parallel with and positioned along the rear face of said lip and the longer of said arms being positioned along the front face of said lip parallel therewith for the entire width of said lip and thereafter extending down said body member of said index card and parallel therewith; locking tongues formed in the longer of said arms, extending through said tongue receiving slits, and positioned between said lip and the shorter of said arms; said folded strip of transparent material having a pair of registering spaced guide rod engaging slots extending upwardly from the lower edges of each of said arms; and at least one flagging device having an indicating tongue and a retaining shoulder positioned between said strip and lip with said indicating tongue extending through one of said flagging device receiving slots.

2. An indexing device, for use in combination with and to be mounted for slidable movement upon a pair of spaced parallel guide rods, comprising a card member having a body portion terminating at its upper end in a lip bent at an angle with respect to the said body portion and having formed therein along said bend line a plurality of spaced horizontal tongue receiving slits; a strip of transparent material folded to form first and second arms and having a plurality of flagging device receiving slots formed in the fold line thereof encompassing said lip with the first of the arms of said strip being parallel with and positioned along the rear face of said lip and the second of said arms being positioned along the front face of said lip parallel

therewith for the entire width of said lip and thereafter extending down said body member of said index card and parallel therewith; locking tongues formed in the second of said arms, extending through said tongue receiving slits, and positioned between said lip and the first of said arms; said strip of transparent material having a pair of registering spaced guide rod engaging slots extending upwardly from the lower edges of each of said arms; and at least one flagging device having an indicating tongue and a retaining shoulder positioned between said strip and lip with said indicating tongue extending through one of said flagging device receiving slots.
